US00D918945S

(12) **United States Design Patent** (10) **Patent No.:** **US D918,945 S**
(45) **Date of Patent:** **** May 11, 2021**

(54) **ELECTRONIC DEVICE WITH GRAPHICAL USER INTERFACE**

(71) Applicant: **Apple Inc.**, Cupertino, CA (US)

(72) Inventors: **Kevin Will Chen**, Sunnyvale, CA (US); **Taylor Gerard Carrigan**, San Francisco, CA (US); **Alan C. Dye**, San Francisco, CA (US); **Charmian Naguit**, Richmond, CA (US)

(73) Assignee: **Apple Inc.**, Cupertino, CA (US)

(**) Term: **15 Years**

(21) Appl. No.: **29/757,003**

(22) Filed: **Nov. 2, 2020**

Related U.S. Application Data

(63) Continuation of application No. 29/662,861, filed on Sep. 10, 2018, now Pat. No. Des. 900,830.

(57) **CLAIM**

The ornamental design for an electronic device with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; FIG. 2 is another embodiment thereof; and,

FIG. 3 is a front view of an electronic device showing the graphical user interface of FIG. 1 applied thereto. The graphical user interface design of FIG. 2 may be similarly applied thereto.

The outer broken lines in the figures show a display screen or portion thereof, or an electronic device having a display screen, and form no part of the claimed design.
